TOOTHBRUSH

Romeo J. Carpentier, Rhinelander, Wis., assignor of twenty-seven and forty-one one-hundredths per cent to Erik Dempster Lindegren, Rhinelander, Wis.

Application November 25, 1931
Serial No. 577,221

2 Claims. (Cl. 15—167)

This invention relates to improvement in tooth brushes.

One of the objects of the present invention is the provision of an improved type of tooth brush, 5 wherein the bristle carrying head is of flexible construction to permit the same to readily conform to the curvature of the teeth during the use of the brush to carry out an efficient cleaning of the teeth and massage of the gums.

10 Another object of the present invention is the provision of improvements in the construction of tooth brushes, wherein the bristle carrying head is formed of a plurality of segments or sections arranged in spaced relation to permit movement 15 of the sections without interference with one another, and are integrally connected by means of a yieldable member which will permit the segments to move independently of one another, so that the bristles on the entire head will 20 readily conform to the contour of the teeth during the cleaning operation.

A further object of the present invention is the provision of an improved tooth brush, wherein the head is constructed of a plurality of yieldably connected bristle sections, with a comparatively rigid handle connected to one of said sections whereby the bristle carrying sections can be used for cleaning the teeth and conform to the curvature thereof and simultaneously impart 30 a massage operation to the gums.

With the above and other objects in view, the invention consists in the novel features of construction, the combination and arrangement of parts hereinafter more fully set forth, pointed 35 out in the claims and shown in the accompanying drawing wherein:

Figure 1 is a detailed section on the line 1—1 of Figure 2, showing the general construction of my improved tooth brush;

40 Figure 2 is a sectional view on the line 2—2 of Figure 1.

Referring more particularly to the drawing, wherein I have illustrated one of the embodiments of my invention, it will be noted that the 45 bristle carrying head is formed of a plurality of sections indicated at 1, 2 and 3. While, in the present instance, I have illustrated the head as formed of three separate sections, it will be apparent that various numbers of sections can be 50 used for carrying out the idea.

Each one of the sections 1, 2 and 3 carry the usual type of bristle indicated at 4 and the several sections have embedded therein and extending longitudinally of the head, a yieldable plate 5 which tapers longitudinally with the larger por-

tion embedded in the inner section 1 and the smaller end embedded in the outer section 3. This tapering of the spring will equalize the lever action on the first joint from the handle end of the brush and will distribute the curving action equally and uniformly on the two joints and thus insure a more even uniform curve without strain. Thus the flexibility of the spring increases toward the free end of the brush head and the intermediate segment of the brush head is prevented from being unduly flexed, so as to prevent the carrying of the outermost brush head segment away from the teeth.

From this it will be apparent that as the several sections are spaced from each other, the 70 yieldable plate 5 will form a yieldable connection between the several sections.

The plate 5 is provided in its longitudinal edges with a plurality of V-shaped notches 6, with one of said notches arranged upon opposite sides of the plate in each of said sections. By providing the notches 6 in the plate 5, the material of which the sections 1, 2 and 3 are formed will extend into the notches 6 and securely retain the plate 5 against any longitudinal movement 80 relative to the said sections. The usual construction of tooth brushes is to mold the bristles 4 into the head, the material of which the brush is formed being such that it can be heated to a plastic condition so that the plate 5 can be 85 readily embedded therein.

Formed integral with the inner section 1, is a handle 7 preferably provided with a tapering shank 8 where it connects to the section 1 and the outer end of the handle is provided with an aperture 9, usually formed in the handles of tooth brushes for suspending a brush on a hook or the like when the same is not in use. The aperture 9 can be omitted from the construction of the brush, as this feature is immaterial of my 95 improvement.

From the above construction taken in connection with the accompanying drawing, it will be apparent that I have provided a simple and inexpensive type of tooth brush, wherein the bristle carrying head is formed of a plurality of yieldably connected sections, so that when the brush is used upon the teeth, the bristle carrying head will readily conform to the contour thereof.

When the brush is brought into engagement with the teeth upon the inner side or the outer side, it will reach all parts of the teeth during the cleaning operation and principally the inside of the teeth which are usually inaccessible 110

and difficult to clean with the standard, rigid brush head.

The device is very simple and inexpensive in construction and can be manufactured and placed on the market at a low cost.

Attention is directed to the fact that the yieldable plate 5 must necessarily be formed from a non-corrosive metal whereby the device as a whole is absolutely sanitary.

10 While I have shown and described the preferred embodiment of my invention, it will be apparent from the foregoing that slight changes may be made in the construction when putting the invention into practice without departing 15 from the spirit of the same or the scope of the appended claims.

I claim:

1. A tooth brush including a handle, a series 20 of spaced bristle carrying sections arranged in alinement and the inner of which is connected to the handle, and a flat flexible strip embedded in all of the sections, said strip being normally substantially straight and having its opposite longitudinal side edges converging from the inner end thereof to the outer end in substantially

straight lines and to cause the outer end of the strip to be of materially less width than the inner end, whereby to allow the sections to flex in a substantially uniform curve corresponding to the curvature of the inner and outer surfaces of the teeth. 80

2. A tooth brush including a handle, a series of spaced bristle carrying sections arranged in alinement and the inner of which is connected to the handle, and a flat flexible strip embedded 85 in all of the sections, said strip being normally substantially straight and having its opposite longitudinal side edges converging from the inner end thereof to the outer end in substantially straight lines and to cause the outer end of the strip to be of materially less width than the inner end whereby to allow the sections to flex in a 90 substantially uniform curve corresponding to the curvature of the inner and outer surfaces of the teeth, and said strip having a pair of notches 95 for each of the sections and into which the latter extend whereby to anchor the sections to the strip, the notches of the respective pairs occurring on opposite side edges of the strip. 100
